UNITED STATES PATENT OFFICE

115,221

DESIGN FOR A DOOR KNOCKER

George J. Stevens, Cleveland, Ohio

Application January 26, 1939, Serial No. 82,622

Term of patent 3½ years

To all whom it may concern:

Be it known that I, George J. Stevens, a citizen of the United States, residing at Cleveland, in the county of Cuyahoga and State of Ohio, have invented a new, original, and ornamental Design for a Door Knocker, of which the following is a specification, reference being had to the accompanying drawing, forming part thereof, and wherein Fig. 1 is a perspective view of a door knocker showing my new design and Fig. 2 is a top plan view of the same.

I claim:

The ornamental design for a door knocker, as shown.

GEORGE J. STEVENS.
